Salim F. Zaloom

By Attorney

Mason Fenwick Lawrence.

UNITED STATES PATENT OFFICE.

SALIM F. ZALOOM, OF BROOKLYN, NEW YORK.

ROASTING MACHINE.

Application filed July 1, 1922. Serial No. 572,338.

To all whom it may concern:

Be it known that I, SALIM F. ZALOOM, a subject of Turkey, residing at Brooklyn, in the county of Kings and State of New York, have invented certain new and useful Improvements in Roasting Machines; and I do hereby declare the following to be a full, clear, and exact description of the invention, such as will enable others skilled in the art 10 to which it appertains to make and use the same.

The objects of this invention are to provide means in connection with a roasting machine for removing undesirable matter from the product being roasted; to provide means for removing dirt and dust from the product as said product is introduced into the roaster; to employ a suction system for this purpose; to permit regulation of the intensity of the suction so as to avoid removal of any of the product; to provide means for removal of shriveled or empty units of the product; to employ the same suction system for this purpose as used for initial removal 25 of the dirt or dust; to provide means for discharging the empty or shriveled units and prevent the same from clogging the suction system; to enable the suction connections to be removed or gotten out of the way when 30 not in use; to secure simplicity of construction and operation and to obtain other advantages and results as may be brought out in the following description.

Referring to the accompanying drawings 35 in which like numerals of reference indicate similar parts throughout the several views.

Figure 1 is a side elevation of a roasting machine with my invention applied thereto;

Figure 2 is a sectional view of a portion 40 of the suction pipe showing the damper and screen therein;

Figures 3 and 5 are elevations of the suction pipe showing the hinged attachment of the branch pipe.

Figure 4 is a sectional view on line 4—4 of Fig. 2;

Figure 6 is a sectional view of the shute from the hopper to the roaster;

Figure 7 is a perspective view of the head 50 for the suction pipe, and

Figure 8 is an end elevation of said head at the side thereof next the pipe.

In the specific embodiment of the invention illustrated in said drawings, reference 55 numeral 1 indicates in general the roasting machine in which the product, such as pis-

tachio nuts, are to be roasted. This roaster contains the usual rotating drum and heat producing elements (not shown) common to roasters of this nature. On the top of the 60 roaster is a suction connection 2 leading to a main suction pipe 3 by means of which steam produced in the process of roasting may be carried off. At the front of the roaster is an opening 4 through which the product is 65 introduced into and removed from the roaster drum. A hinged closure 5 is provided at this opening 4 arranged to swing downwardly and operate as a shute for introducing the product into the roaster. 70

The product is preferably introduced first into a hopper 6 above the opening 4 by any suitable means. Except as for such opening as necessary for introduction of the product into this hopper, the same is preferably 75 closed so that dust resulting from introduction of the product will not escape. From the closed top 7 of said hopper, leads a suction pipe 8 to the main suction pipe 3, and a sufficient suction is employed for removing 80 the dirt and dust from the product as it enters the hopper. In order to regulate the suction, I preferably provide a damper 9 in the pipe 8 between the main suction pipe 3 and the hopper, and this damper may be 85 turned to more or less cut off the interior passage of said pipe to obtain just enough suction to carry off the dirt without carrying any of the product away. The bottom of the hopper 6 is provided with a gate 10 90 by means of which the opening to a hopper shute 11 may be opened or closed. This hopper shute may be turned so that its lower end is directed into opening 4 of the roaster, or may be turned so the lower end is directed 95 away from the roaster so as not to interfere with free access to said opening. It is to be understood that in operation, the product is introduced into the hopper 6 with the suction removing the dirt and dust while the 100 product is being introduced, and the hopper shute 11 is directed into the roaster with the gate 10 open so the product will pass into the roaster for treatment. When a sufficient quantity of the product is introduced into the roaster, the gate 10 of the hopper is 105 closed and the hopper shute 11 removed from the opening 4 of the roaster, at which time the roasting process is started and is continued until the product is sufficiently 110 treated.

For use during treatment or roasting of

the product, I provide means for removal of empty units of the product, and for convenience employ the suction system also for this purpose. Preferably this removal of the empty units is accomplished by means separate from the hopper and shute 11, but obviously if found more desirable the same means might be utilized. As shown, I provide a stand-pipe 12 connected at its upper end to the main suction pipe 3, and provided at its lower end with a suitable closure 13 which may be retained shut when desired or opened as becomes necessary or desirable. Intermediate the ends of said stand-pipe is a branch-pipe 14 hinged as at 15 so it may be swung with its lower end in proximity to the shute 5. Above the introduction of this branch-pipe 14 in the stand-pipe 12 is a screen 16 for preventing any of the product units from passing into the main vacuum pipe 3 or from passing out of the vertically arranged portion of the stand-pipe. If so desired, a damper 17 may be provided in the stand-pipe for regulating the intensity of the suction utilized in connection with this part of the system. In operation, the lower end of the branch-pipe 14 is arranged to be in close proximity with the product as it passes the opening 4 during agitation within the roaster, and the intensity of the suction is regulated to act only upon shriveled or empty units of the product, the good units being heavy enough to remain in the roaster unaffected by the suction. The empty or otherwise undesirable units are drawn up the branch-pipe 14 and into the stand-pipe 12, but will be prevented from going further by virtue of screen 16. When the stand-pipe 12 becomes full or clogged, opening of closure 13 at the bottom thereof will permit the empty shells to drop out of the stand-pipe into a suitable receptacle 18, after which the closure 13 is closed so the suction will still function upon the product in the roaster. In this way, it will be seen that both dirt and undesirable units of the product are removed from the said product so the same is improved in appearance and character and increasingly edible and salable.

As shown in the drawings, it is preferable to provide a suitable head 19 on branch-pipe 14 which may be inserted in the opening 4 of the roaster and substantially fill the same. This head 19 preferably is box like in shape and pipe 14 enters the same adjacent one side and extends a distance toward the inner head as shown at 20, with a flange 21 flaring toward the other side of the said box like structure so as to have a tendency to deflect the units of the product into the inner end 20 of said branch-pipe 14. The outer end of said box like structure, between the branch-pipe 14 and the side wall furthest therefrom is

provided with a hand hole 22 with suitable closure 23 by means of which the operator may view the interior of the roaster while the device is in place or may reach in and obtain some of the product for testing or other purposes. In order to positively pass the product close to the end 20 of the branch-pipe, I preferably provide a deflector 24 supported by suitable brackets 25 at a spaced distance from the inner end of the box like structure, said deflector sloping toward the branch-pipe. In this way, the product is brought within the range of the suction and the empty shells will be thereby withdrawn.

Obviously detail changes and modifications may be made in the construction and use of my improved invention, and I do not wish to be understood as restricting myself to the exact structure shown except as required by the following claims when construed in the light of the prior art.

Having thus described my invention, I claim:—

1. In combination with a roasting machine, means for removing undesirable matter from the raw material preliminary to and during the roasting operation. 90
2. In combination with a roasting machine, a suction system for removing undesirable matter from the raw material preliminary to and during the roasting operation. 95
3. In combination with a roasting machine, a suction system for removing undesirable matter from the raw material as it enters and during treatment in the roasting machine. 100
4. In combination with a roasting machine, a hopper, a shute for passing the raw material from the hopper to the roasting machine, and means for removing dirt and dust from the raw material in the hopper. 105
5. In combination with a roasting machine, a hopper, a shute for introducing the raw material from the hopper to the roasting machine, a suction pipe connected with the hopper for removing the dirt and dust from the product in the hopper. 110
6. In combination with a roasting machine, a suction stand-pipe, a branch-pipe adapted to be positioned adjacent the material during treatment thereof in the roasting machine so as to withdraw undesirable matter from the product. 120
7. In combination with a roasting machine, a suction stand-pipe, a branch-pipe adapted to be positioned adjacent the material within the roasting machine so as to withdraw undesirable matter therefrom, and a screen in the stand-pipe for preventing the withdrawn matter from passing out of the stand-pipe. 125
8. In combination with a roasting ma-

chine, a suction stand-pipe, a branch-pipe adapted to be positioned adjacent the material within the roasting machine so as to withdraw undesirable matter therefrom, a screen in the stand-pipe above the branch-pipe for preventing the undesirable matter from passing upwardly out of the stand-pipe, and a closure at the bottom of the stand-pipe adapted to be opened for permitting said matter to escape therethrough.

9. In combination with a roasting machine, a suction pipe for removing empty or shriveled units of the material during treatment thereof in the machine, and a deflector for causing the material to pass close to the entrance of said pipe within the machine.

In testimony whereof I affix my signature.

SALIM F. ZALOOM.
